UNITED STATES PATENT OFFICE

PERCIVAL P. HENSHALL, OF COLUMBUS, OHIO, ASSIGNOR TO THE BUCKEYE BLOWER COMPANY, OF COLUMBUS, OHIO, A CORPORATION OF OHIO

CROSS FLOW RADIATOR

Application filed June 1, 1931. Serial No. 541,166.

This invention relates to improvements in cross flow radiators, and has for its object to provide a radiator and ventilating apparatus in which the air is uniformly heated 5 and discharged into a room in a uniform temperature condition.

It is also an object of this invention to provide, in connection with a ventilating and heating apparatus, means for creating a current of air and directing the air from outside of the building to a point on the inside, and then this air is discharged into the building to allow it to be retarded in its forward movement and expand, and after it has expanded, pass over heating fins by which the air is uniformly heated and tempered for discharge into a room or building.

It is also an object of this invention to provide, in connection with a ventilating and heating apparatus, means for creating a current of air, means to allow the current of air to expand and lose part of its velocity, and after the air has expanded to pass through a heating element consisting of a plurality of longitudinally arranged fins. It has been found in actual practice that by having the fins arranged in a longitudinal position with relation to the casing in which the fan element is located and sufficiently removed from the fan element, the air can expand and that the amount of material in the radiator may be materially reduced.

Under ordinary conditions a radiator six 35 inches high would be necessary if the fins run crosswise of the casing, but with the longitudinal arrangement and the expansion space radiator fins no higher than two and a half inches may be used, and produce the same result as radiators six inches high 40 would produce if the fins were crosswise of the casing instead of longitudinal.

By reducing the height of the radiator the total height of the casing may be reduced, 45 thereby enabling the whole unit to be used under lower windows than with higher heaters and larger casings.

These and other advantages will appear from the following description, taken in connection with the drawings, in which there is

shown a preferred embodiment of this invention.

Referring to the drawings:

Figure 1 is a vertical section on the line 1—1 of Figure 3. 55

Figure 2 is a view showing a part of the front of the casing.

Figure 3 is a vertical section on the line 3—3 of Figure 1. 60

Figure 4 is a top plan view of a radiator. 65

Figure 5 is a section on the line 5—5 of Figure 4.

Figure 6 is a section on the line 6—6 of Figure 5. 70

Figure 7 is an end elevation of the radiator.

This air conditioning and air heating apparatus is inclosed within a casing 1, which has an inlet opening 2 for the admission of fresh air into the interior of the casing. The admission of fresh air into the casing is regulated by means of a damper 3, as shown in Figure 3. This damper may be arranged to have automatic control or it may be manually controlled. The damper control is no part of this invention. 75

The lower part of the casing is designated a chamber 4 into which cool, fresh air is admitted from the outside through the inlet 2. This chamber has side walls 5, as shown in Figure 1, and has an outlet 6 through which the air passes from the chamber into a fan chamber 7. The fan chamber in the present instance has two fans. Different numbers of fans may be used, depending upon the size of the casing and the size of the fans. 80

Fan casings 8 are shown to be convolute in form with lateral openings therein for the admission of air into the casing. These lateral openings or inlets are indicated by the numeral 9. In the casing is a fan 10 operated by a motor 11, which has a shaft 12 for operating the fans and to which the fans are attached. While the inlets to the fans are laterally disposed the outlets 13 lead upwardly into an expansion chamber, to be later described. The inlet part of the fan is funnel-shaped so as to direct the air from the fan chamber into the fan casings so that it 100

may be delivered for heating purposes to the expansion chamber.

In each side of the main casing and attached to the walls thereof are brackets 14, which have downwardly inclined parts 15 which tend to direct the incoming air into the fan casings. The part of each bracket immediately above the inclined part is formed into a shoulder 16 for supporting a plate 17 immediately above the exit or outlet from the fan casings. This plate has as many openings therein as there are fans in the fan chamber, and adjacent each opening and to each side thereof there is formed a turned-down flange 19 which projects into the outlet part of each fan casing and serves, in cooperation with the fan casings, to direct the air through openings 18 in the plate.

Located in the openings 18 and immediately above the outlet from the fan casings are diagonally disposed deflectors 20. In the present instance four of these deflectors are shown in connection with each fan, and of these four deflectors two slant upwardly in one direction and the other two slant upwardly in another direction. By this means the air as it leaves the fans is divided into various streams that are directed to all parts of the expansion chamber immediately above the plate 17. When the air leaves the fan casings it is more or less compressed and remains compressed until it passes through the openings in the plate 17, after which it expands uniformly due to its distribution to all parts of the chamber.

This expansion chamber permits the air to expand and lose a part of its velocity so that as it reaches the radiator its motion is not so rapid and it has substantially a very broad cross sectional area of movement at substantially a uniform speed for all cross sections of the area. The upper parts of the brackets 14 are formed into ledges 21 which support legs 22, extending downwardly from a heater or radiator 23 which has at each end a right angular projection 23a. The legs 22, with the brackets 14, form the expansion chamber 24, into which the air passes after leaving the fans and in which it expands before entering the heater or radiator.

It will be noticed from the arrangement of the deflectors that the air is directed in currents longitudinally of the casing, and in order that the radiator fins may have the greatest effect upon the air they are likewise arranged longitudinally of the casing so that there is an equal distribution of air through the length of the radiator.

The heater has an inlet 25 and an outlet 26 connected to the projections for the admission and discharge of hot water or steam for heating purposes. The nature of the radiator or heater is shown well in Figure

4. The radiator is composed of two casings or headers connected by pipes or tubes 27.

Into one of these casings the hot water or steam is admitted through the inlet, and from this casing it passes into the other casing through the pipes 27, and from the other casing out through the discharge or outlet 26. The two casings are also connected by a pipe 27a between one end of one casing and the projection on the other casing.

In order to provide radiating surfaces the fins 28 are located in a vertical position on the pipes 27. These fins are made of some good conducting material so that the heat from the pipes is conducted into the air as it passes over the fins. The fins may be made of copper, aluminum or any other suitable material. Extending over the top of the main casing is a cover 29, which has an outlet opening 30 therein through which the air passes from the main casing after passing through the heater and about the heating fins. This outlet may have provided therein louvers or means for controlling the current of air from the main casing into the room or building heated by the apparatus.

I desire to comprehend within my invention such modifications as may be embraced within my claims and the scope of my invention.

Having thus fully described my invention, what I claim as new and desire to secure by Letters Patent, is:

1. In a ventilating apparatus, a casing having an inlet chamber, an expansion chamber, an outlet adjacent the expansion chamber and a partition having a passageway 100 therein between the inlet chamber and the expansion chamber, means to cause a current of air through the casing from the inlet chamber through the expansion chamber and out at the outlet, a plurality of oppositely inclined deflectors across the passageway to disperse the air as it passes through the passageway whereby it more readily and evenly expands in the expansion chamber, and means adjacent the outlet to heat the expanding air.

2. In a ventilating apparatus, a casing having an inlet chamber, an expansion chamber, an outlet adjacent the expansion chamber and a partition having a passageway 111 therein between the inlet chamber and the expansion chamber, means to cause a current of air through the casing from the inlet chamber through the expansion chamber and out at the outlet, a plurality of oppositely inclined deflectors across the passageway to disperse the air as it passes through the passageway whereby it more readily and evenly expands in the expansion chamber, and means adjacent the outlet to heat the expanding air, said heating means including a plurality of closely arranged narrow fins arranged across the lines of dispersion of the air.

3. In a ventilating apparatus, an oblong expansion chamber, means to force air into

and through the chamber, means to cause the entering air to move diagonally in conflicting streams across the chamber whereby the air is mixed in the chamber as it expands, 5 and means to heat the air leaving the chamber, consisting of pipes arranged transversely of the chamber, and radiating fins on the pipes longitudinally of the chamber.

4. In a ventilating apparatus, an oblong 10 expansion chamber, transversely diverging deflectors to cause air to enter the casing in diagonal conflicting currents, and means to heat the air as it leaves the chamber, said means consisting of heat pipes and radiating 15 fins thereon, said fins being arranged longitudinally of the chamber so the fins will cut longitudinally through the currents of air.

5. In a heating and ventilating unit, means 20 for moving air through the unit, a radiator therein having headers arranged parallel to the front and back of the unit, and transverse intercommunicating pipes and longitudinally arranged fins comprising plates 25 vertically disposed parallel to the front and back of the unit, each header having at one end an angular extension projecting toward the other header at its end.

6. A new article of manufacture for use 30 as a radiator comprising longitudinally extending headers having short transverse supply and exit pipes engaging portions of transverse pipes connecting said headers, one header having at one end a transverse extension projecting toward one end of the 35 other header and connected thereto by a pipe.

7. A new article of manufacture for use 40 as a radiator comprising longitudinally extending headers having short transverse supply and exit pipes engaging portions of transverse pipes connecting said headers, and fins arranged vertically on said transverse pipes parallel to said headers, each header having at one end an angular extension projecting 45 toward the other header, one of said projections being connected to the other header by a pipe.

8. A new article of manufacture for use 50 as a radiator comprising longitudinally extending headers, each having at one end a short transverse extension with an opening therein and transverse pipes connecting said headers, and fins arranged vertically on said transverse pipes parallel to said headers comprising 55 continuous plates.

9. In a ventilating apparatus, a casing 60 having an inlet and an outlet, a fan in the casing adjacent the inlet, a heating means across the outlet, said heating means including a plurality of closely arranged narrow radiating fins, an expansion chamber in the casing between the fan and the heating means, and means adjacent the fan to disperse the 65 air of the stream of air leaving the fan, said last-named means comprising a plurality of

deflectors inclined in one direction and a plurality of deflectors inclined in another direction, whereby the air expands more rapidly and evenly in the expansion chamber before reaching the heating means. 70

10. A new article of manufacture for use as a radiator comprising longitudinally extending headers, each having at one end a short transverse extension with an opening therein and transverse pipes connecting said 75 headers, fins arranged vertically on said transverse pipes parallel to said headers comprising continuous plates, and means for connecting one end of one of said headers with the angular extension of the other header. 80

11. A new article of manufacture for use 85 as a radiator comprising a pair of headers spaced from one another arranged in parallel relationship, having angular extensions on opposite ends of the respective headers extending vertically towards the other header, a plurality of spaced interconnecting transverse pipes connecting said headers, and plates mounted on said transverse pipes in spaced relationship to one another and parallel to said longitudinal headers. 90

12. A new article of manufacture for use 95 as a radiator comprising a pair of headers spaced from one another arranged in parallel relationship, having angular extensions on opposite ends of the respective headers extending vertically towards the other header, a plurality of spaced interconnecting transverse pipes connecting said headers, plates mounted on said transverse pipes in spaced relationship to one another and parallel to said longitudinal headers, and means 100 interconnecting the end of one header with the angular extension of the other header. 105

13. In combination, a unit heater and ventilator comprising a casing having inlet and outlet openings at respective ends, a blower therein adapted to draw air in the casing and deliver it out of the casing, an expansion chamber above said blower, and a relatively 110 shallow radiator mounted over the top of said expansion chamber adjacent the outlet of said casing, said radiator having a plurality of transversely arranged heating pipes and a plurality of spaced radiating plates 115 mounted thereon transversely thereof. 120

14. In combination in a heating and ventilating unit, of a casing having inlet and outlet openings, a blower therein, an expansion chamber for receiving air from the blower of relatively great depth, and a relatively shallow radiator mounted thereon having longitudinally extending radiation plates arranged in the plane of the exit of the air and supporting heating pipes arranged transversely thereto. 125

In testimony whereof, I affix my signature.

PERCIVAL P. HENSHALL.
